(54) **SHEARING CLOTH**

(76) Inventor: **Jesse Molleneux**

The Schedule referred to in these Letters Patent and making
part of the same containing a description of the works of the said James
Mathewson, himself, of his machine for calicoing Weston cloth.

A frame of wood or metal is constructed, consisting of four upright
corner posts, connected by transverse bars, at right angles. This square frame
is three feet high, as many feet in length, and of the same number of feet in
breadth. Being thus rendered firm and strong, it is ready to support the ma-
chinery. Though it is to be understood that the dimensions may be greater
or less in every respect as may be deemed necessary.

The two back or hinder posts are about a foot higher or longer than
the fore ones. This is done for the reception of a moveable cylinder, in which is
wound or rolled a turn of cloth. This cloth is about a yard in length, and one
of its ends is fastened to the cylinder, while the other is fastened by hooks to the
end of the piece of cloth intended for shearing. The ends of the cylinder are
received into grooves in the posts at each extremity, and can be taken out and
put in at pleasure.

The piece of cloth intended to be sheared is hooked, fast and rolled
up upon the cylinder so revolving on its axis. On unrolling it passes first
over and along another cylinder, situated almost immediately below it,
at the distance of six inches or thereabouts. The former of these is called the first,
and the latter the second cylinder. This second cylinder is armed with short
brads whose operation is to hold the cloth equal and steady, as well as to ex-
pand it as it is unrolled and pulled along.

As it thus passes along, it is applied to a third cylinder. Here, as it
is uniformly and duly spind and stretched, it is subjected to the operation of
the shears or cutters, presently to be described.

Having undergone the operation of shearing, the cloth is moved
successively along to the fourth cylinder, situated immediately under the
third, and almost in contact with it. Thence it descends to the floor, with
a grating or basket placed for the purpose of receiving it.

Such is the apparatus for rolling, controlling, applying and ma-
rining the cloth.

I claim further as but of improvement, in the machine described as the basis of this my machinery for cutting a flannel blanket. This flannel is about two feet and one half long and one wide, though its dimensions may be varied to suit the circumstances of the case. One edge of the flannel is mounted by means of a wooden bar with a pair of coarse pins of cloth which forms a bag to receive the flaks, and the other edge or front part of the flannel is applied on its upper side to the action of certain moveable metallic bodies called cutters.

These cutters are eighteen in number they may be more or less. They are connected obliquely to one of the transverse timbers of the machine. This timber lies horizontally, and the cutters project from the posterior or inner side. When at rest they form an angle of about twenty two degrees; though this may vary at discretion. In this slanting situation they are fastened at one extremity to the transverse timber by rivets or pins, and at the other extremity to another horizontal and parallel timber, by as many metallic bars. There is a slape of metal connecting these bars with the cutters. And there are also springs equally numerous with the cutters, and made of good elastic wire. These springs are so constructed as to act or push downward. They proceed from a horizontal timber lying parallel to and very near these which sustains the cutters, and immediately above it. They project from it at a similar angle. At about the length of ten inches, which is twice the length of the cutters, these springs are bent downward at a right angle, and terminate in a fork or crotch, passing upon the backs of the cutters, and applying them closely, yet gently to the blade or lower cutter.

The timber to which the cutters are connected, is also connected to the timber that supports the springs by two or more hinges and these two timbers are further connected by two or more screws. The operation of these hinges and screws, is to regulate the pressure of the springs upon the cutters, so that it may be more or less forcible, according to the workman.

The eighteen bars are connected to a horizontal timber, to which is joined a perpendicular piece of copper or other metal, called a scrapper. This scrapper is two feet and a half long and one wide and a half wide, one or half. Its operation is to raise the nap on the cloth passing beneath it, in its way to the shears. There is a pinion on the part of the machine supporting the scrapper.

have with a small spring and have a certain number by which they may all be clamped together when the blade and the third cylinder on which it rests, lie high enough to pick up and adjust the fibers of cloth intended to be sheared, and at the same time to facilitate removal.

To enable the edge of the blade to lie closer to or further from the cloth and the cutters to shear more or less of the nap from the surface, there are two screws behind and in the rear of it which by tightening and pushing it forward, make the instrument cut the longer, and by relaxing and suffering it to recede, cause it to shear the closer.

For the purpose of enabling the fourth cylinder to perform its functions there is accurately in dressing the cloth regularly and smoothly along after the operation of the shears has been performed, the two extremities of its nose are suspended on wires which by their strength and elasticity, press it upwards towards the third cylinder with the requisite force.

And in like manner the two easy and rapid motion of the third cylinder is prevented and the cloth is forced to sit tight to the blade by means of two levers acted upon by two springs which are supported by the two longer joints of the frame one is each.

The machine may be put into action by man, horse or other animals or by wind or water. The moving powers are cranks, axles, wheels, whirrions, cog, chains, and bands.

One side of the apparatus is calculated to give motion to the cloth, as it passes from the first to the fourth cylinder, and the other side to give action to the cutters which flying upon the blade perform the office of shears.

The whole movements are so regulated as to bring the cloth successively and regularly along, so that its fuzzy or nap may be removed as it passes smoothly and neatly from every portion of the surface.

That a great excellence, and indeed the most valuable peculiarity in this machine and invention, is that the cloth can never be cut to pieces or spoiled by the shears. For the cutters are so nicely regulated and graduated, that if by any accident the cloth should get between them and the blade, the spring will yield and give way, before the cloth can be damaged.

And in this particular the invention is comprised in a general and broadened performance of any thing of this kind now or hereafter known.

I further claim a method of following cloth by a small machine and invention, of three quarters of a yard in width, and but once over a piece of cloth once through the machine. And the same time proposed to construct two machines on the same principles and in the same general form, wide enough for shearing cloth in quarters wide, or of greater width if required. It is moreover intended to adapt such wide machines to the shearing of two pieces of narrow cloth at the same time by setting the foot of another post in the middle of the hindermost transverse bar which rising with the hand behind the second cylinder is made with its upper part to stand firm at an equal distance from the two main posts of the frame having a similar groove on each side to receive the end of the first cylinder, on which the cloth is pulled. The top of this post is fastened to a cross bar of wood or metal, on the top of the main posts and the two cylinders for receiving the narrow pieces of cloth after the same manner that the first cylinder does in the former part of this specification. This post is to be so framed as to be put in and taken out as may best suit the business to be done.
